UNITED STATES PATENT OFFICE.

FRANK HOWARD MAYER, OF DENVER, COLORADO.

GEARING FOR WASHING-MACHINES.

1,385,464.

Specification of Letters Patent. Patented July 26, 1921.

Application filed January 17, 1920. Serial No. 352,097.

To all whom it may concern:

Be it known that I, FRANK HOWARD MAYER, a citizen of the United States, and a resident of Denver, in the county of Denver and State of Colorado, have invented certain new and useful Improvements in Gearing for Washing-Machines, of which the following is a specification.

My invention relates to improvements in washing machines, it being more particularly an improvement in the drive gearing therefor, and it consists in the constructions, combinations and arrangements herein described and claimed.

15 The foremost object of my invention is to provide a washing machine which has mutilated drive gearing for oscillating the clothes cradle so as to wash the clothes, and a continuous gear for subsequently revolving 20 the cradle so as to expel the water from the clothes.

A further object of the invention is to provide a novel arrangement of drive gearing for the clothes cradle of a washing machine or the like, which includes a shiftable pinion arranged to engage either a mutilated or a continuous internal spur gear.

25 A further object of the invention is to provide a novel form of gearing adaptable wherever either a continuous or an intermittently oscillatable motion is required.

Other objects and advantages will appear in the following specification, reference being had to the accompanying drawings, in 35 which:—

Figure 1 is an end elevation of the improved gearing, illustrating its application, for example, to a washing machine.

Fig. 2 is a detail sectional view of the improved drive gearing, taken substantially on the line 2—2 of Fig. 1, and

Fig. 3 is a detail front elevation thereof, parts being broken away.

It is desired to illustrate one mode of application of the improved gearing to a washing machine, but it should be pointed out that the same gearing can be well applied to other devices such as liquid mixers, mixers of semi-liquid and pulverulent materials, like paint, concrete, sand, etc. The washing machine comprises a tub 1 which is mounted upon a suitable frame 2, has a lid 3 hinged at 4 at the front, and is provided with suitable clamp means (not shown) by which the lid is firmly secured in the closed opening so

as to prevent water spilling out. The rolls of a wringer 7 are operated by pulley and belt connections 8 leading to the electric motor 9 on the back of the frame 2.

This motor has a driving connection 10 to the master drive gear 11 which has a continuous internal spur gear 12 nearest the tub 1, an internal mutilated gear 13 next to the gear 12 and a smaller mutilated gear 14 integral with the spokes 15. All of the mentioned parts of the master drive gear 11, are cast integrally with each other and with the hub 16 which has trunnions 17 running in babbited journals 18 of a bracket or standard 19.

70 The master drive gear 11 revolves continuously in one direction while the motor 9 is in operation. There is a two-diameter pinion 20, 21 on the cradle stub shaft 22 at the right in Fig. 2, this pinion including a sleeve 75 23 which facilitates the supporting and sliding of the pinion on the stub shaft. When the two-diameter pinion is in the outermost position indicated in Fig. 2, then the gear portion of the mutilated gears 13, 14 alternately mesh with the pinions 20, 21 so that an oscillatory movement of the clothes cradle 6 carried by the shaft 22, results.

When the latch 24, pivotally mounted in the sleeve 23 and pressed down by the leaf spring 25, is raised and the two-diameter gear 20, 21 slid inwardly on the stub shaft 22, then the large pinion 20 meshes with the continuous internal gear 12 so that the clothes cradle 6 is revolved continuously in 90 one direction so as to expel the water from the clothes by centrifugal action. At this time, the pinion 21 is out of meshing position with the mutilated gear 14, it being observed that the mutilated gear 13 cannot 95 reach the pinion 21 and so the revolving of the clothes cradle goes on uninterruptedly.

100 While the two-diameter pinion 20, 21 is free to be slid in and out on the stub shaft 22, by any suitable means not shown in the drawings, still it cannot turn in respect to the stub shaft, because the upper part of the stub shaft is flattened as at 26 to provide a key for the pinion. This flattened part has outer and inner recesses 27, 28 to receive 105 the latch 24 when the two-diameter pinion is at its respective positions.

The operation of the gearing may be briefly outlined to advantage.

110 Normally the two-diameter pinion 20—21

should be in the position shown in Fig. 2, so that when the electric motor 9 is started and the master drive gear 11 is continuously rotated in one direction, the mutilated gears 5 13, 14 alternately engage the pinions 20 and 21, so that the cradle inside of the tub 1 is rotated first in one direction then in the other. The clothes on the inside tumbling over the ribbed surface of the cradle, are 10 thoroughly rubbed without entangling.

After the rubbing action has continued a sufficient length of time, the operator shifts the sleeve 23 inwardly by any suitable means, it being necessary of course to lift 15 the latch 24, so that the large pinion 20 engages the continuous internal gear 12 and the continuous uni-directional rotation of the master drive gear 11 is transmitted directly to the cradle 6 so that it is caused to 20 rapidly revolve in one direction. It should be first explained, however, that before this is done, the cock is opened to let out the dirty water, clear water having been run in thereafter so as to thoroughly rinse the clothes.

25 It is now seen that the cradle 6 is rapidly revolved, the water being expelled from the clothes by virtue of the centrifugal action. It is not necessary to employ the wringer 7 at all, because the clothes can be thoroughly 30 dried by centrifugal action in the manner stated, the wringer being provided merely as an auxiliary for those who may desire to use it.

While the construction and arrangement 35 of the improved washing machine, as herein described and claimed, is that of a generally preferred form, obviously modifications and changes can be made without departing from the spirit of the invention or the scope of 40 the claims.

I claim:—

1. Gearing, including a rotatable shaft, with a shiftable two-diameter pinion, and a uni-directionally driven master gear with 45 mutilated gear portions for oscillating said shaft when the two-diameter pinion is in registration therewith, and with a continuous gear for revolving said shaft when a

corresponding portion of said pinion is shifted into engagement therewith. 50

2. Gearing, including a flattened-ended shaft, a two-diameter pinion shiftable on said end, with means for holding it in the shifted positions; and a uni-directionally driven master gear in relatively fixed relationship, having mutilated gear portions with which said pinion co-operates when shifted to oscillate the shaft, and a continuous gear with which a portion of said pinion meshes when shifted, to continuously revolve 60 the shaft. 55

3. Gearing, including a flattened-ended stub shaft, a uni-directionally driven master drive gear suitably journaled in relatively fixed relationship to the stub shaft, including mutilated and continuous gear portions; and a two-diameter pinion slidable on the flattened-ended stub shaft, with means for holding it in either of two adjustments, co-operating with the mutilated portions to 70 oscillate the shaft, and with the continuous gear portions to continuously rotate the shaft. 65

4. The combination, of a rotatable member having a stub shaft, a relatively stationarily journaled master drive gear, with mutilated gear portions respectively adjacent the rim and hub, and a continuous gear portion adjacent the rim; and a two-diameter pinion slidably carried by said stub shaft 80 projecting between the mutilated gear portions, producing an oscillating member movement when in registration with the mutilated gear portions, and a continuous member rotation when in mesh with the continuous gear. 75 85

5. In combination with a container including a standard with journal bearings, and an integrally cast master drive gear including a hub between the bearings, trunnions reclining in the bearings, and a rim spoke-supported from the hub, including continuous and mutilated gear portions, and a mutilated gear on the spoke near the hub. 90

FRANK HOWARD MAYER.
